(57) **CLAIM**

The ornamental design for a glove pad, as shown and described.

DESCRIPTION

FIG. 1 is a perspective view of a glove pad in accordance with the subject invention;

FIG. 2 is a top view of the glove pad in accordance with the subject invention;

FIG. 3 is a side view along arrows 3—3 in FIG. 2;

FIG. 4 is a side view along arrows 4—4 in FIG. 2;

FIG. 5 is a side view from the right side of the glove pad in FIG. 2; and,

FIG. 6 is a side view from the left side of the glove pad in FIG. 2.

The bottom view of FIG. 2 is omitted because it is plain and unornamental.

The broken lines illustrated herein are environmental only and not part of the claimed design.
